UNITED STATES PATENT OFFICE.

WILLIAM W. LE GRANDE, OF LOUISVILLE, KENTUCKY, ASSIGNOR OF ELEVEN TWENTY-FOURTHS TO H. R. DERING, W. W. DERING, AND T. H. UPPERMANN, ALL OF SAME PLACE.

RAILWAY-SIGNAL.

SPECIFICATION forming part of Letters Patent No. 341,666, dated May 11, 1886.

Application filed June 29, 1885. Serial No. 170,085. (No model.)

To all whom it may concern:

Be it known that I, WILLIAM W. LE GRANDE, a citizen of the United States of America, residing at Louisville, in the county of Jefferson and State of Kentucky, have invented certain new and useful Improvements in Electro-Mechanical Signal Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to improvements in electro-mechanical signal devices of that class which is provided with an armature arranged to rotate on its axis in a plane parallel with the face of the poles of the electro-magnet net.

20 The object of my invention is to provide apparatus for operating electrical signals, which can be controlled by the electric currents either in a common circuit or specially arranged circuits.

25 My invention consists in the peculiarly-constructed armature consisting of independent circular segments of steel rigidly connected by a non-magnetic bar adjustably fitted to a 30 shaft arranged parallel to the cores of an electro-magnet and adapted to rotate on a plane parallel with the face of the poles of the magnet, in combination with an electro-magnet.

35 My invention further consists in the means for permanently magnetizing the armature, so that when the current of electricity traverses the coils of the magnet in one direction the armature will be held in a certain position, and that when the current is reversed and 40 traverses the coils in the opposite direction the armature will be reversed and the signaling device display opposite indications.

45 My invention further consists in signal-magnets, in combination with the main line of circuit, whereby the signals are operated directly by the current traversing the main-line circuit.

50 My invention also consists in the novel arrangement and combination of elements, as

will be hereinafter more fully described, and 50 specifically pointed out in the claims.

I have fully illustrated my improvements in the accompanying drawings, wherein Figure 1 is a front elevation of the electro-magnet, the armature and its shaft, and a signal 55 fixed thereto. Figs. 2 and 3 are plan views of the apparatus, showing the armature in different positions. Fig. 4 is an enlarged view in elevation. Fig. 5 is a similar view in plan, showing the construction of the armature; and 60 Fig. 6 is a plan view of a section or block of railroad with my improved devices applied in operative connection.

The letter A designates an electro-magnet of a well-known construction, preferably 65 mounted in an upright position upon the base A'. The cores of the electro-magnet are connected together by a soft-iron yoke or bar, a, in the usual manner.

The letter B designates my improved armature. This is comprised of two flat bars of 70 steel, b b', which are bent in circular shape and arranged with their ends approaching, and are rigidly secured together by a non-magnetic bar, b². This non-magnetic bar b² is 75

preferably fixed to the arms or segments of the armature near the opposite ends of the arms, in order that the greater part of each arm shall be on opposite sides of the connecting-bar, and thus permit the armature to traverse a greater distance over the poles when 80 acted on by the circuit. In the center of the connecting-bar is formed an aperture, b⁴, through which is passed a shaft, b⁵, which is fixed in the connecting-bar by means of a set-screw, 85 b⁶. Thus the armature may be adjusted to any positions on the shaft desired, and there secured by means of this set-screw. By the same means the rotation of the armature over the poles may be limited by moving the segments laterally. The shaft b⁵ is pivoted in the 90 base-piece and turns in a hole in the cross-piece b⁸, supported on standards b⁹. A sleeve, c, is fitted to the shaft b⁵, and in the sleeve is secured a stop-pin, c', the arm of which projects upward, substantially as shown, and lodges against the edge of the cross-piece b⁸, 95 whereby the rotation of the armature is posi-

tively limited. On the end of the shaft b^5 , projecting above the cross-piece, is fitted a sleeve and socket, c^2 , to which the signal-rod carrying the signal is connected, substantially as shown. On the shaft b^5 , preferably below the armature, is secured a sleeve, c^3 , having a pin, c^4 , projecting therefrom, and to this pin is secured a cord, c^5 , which is passed over a grooved pulley, c^6 , journaled to one of the standards, 10 and a weight, c^7 , is attached to the free end of the cord, the purpose being to give automatic movement to the signal whenever the current is broken and turn it to a position of "danger."

It will be noticed that when a current of 15 electricity saturates the magnets, both a repellent and attractive force is brought to bear for holding the signal-banners in a position to indicate "safety."

In Fig. 6 of the drawings I have demonstrated a plan view of an insulated section or block of railroad having the electro-magnetic signals arranged at each end of the block of road, and a battery-box, with opposing batteries therein, and have indicated the course 20 of the currents thereon. Referring thereto, the letter D designates the battery-box containing a large battery, d , coupled for quantity, and from the negative side of this battery, designated d' , is carried a conducting-wire, d^2 , 25 which is connected with the track-wire d^3 at the other end of the section of track, as designated at d^4 , and from this point is carried a wire, d^5 , which is connected to one side of the electro-magnet d^6 , which magnet is of the construction and arrangement of parts or elements heretofore described. Connected to and leading from the other side of this electro-magnet is a wire, d^7 , which is carried along the track and connected to the signal-magnet 30 d^8 . From the other side of the signal-magnet d^8 , leading from thence to the negative side of the battery E, located in the battery-box, is another wire, d^9 . This battery E is of smaller quantity than the larger battery, d , and for 35 the purpose hereinafter mentioned. A wire, e , is connected with the copper side of battery E, and from thence is extended to and connects with the track-wire e' , which is extended, as shown, and connected in turn at the other 40 end to the positive side of the battery d , thus completing a circuit in which the two opposing batteries, being of relatively different powers or strength, act to hold the signals at "safety" when there is no train or other ob- 45 struction intervening to break the circuit on the section or block of road. This condition is accomplished by the influence of the large battery, d , which, being the stronger, acts with 50 controlling force over the weaker current, and 55 directs the circuit in the direction indicated by arrows, when not interrupted by a train passing over the section of track included within the circuit or other break in the line. When, how- 60 ever, a train enters on the block or track from 65 either end, the main or stronger battery d will be cut out or "short-circuited" by the connection made across the track through the

wheels and axle of the car, as indicated by the crossing arrow in front of the dummy, and the smaller and weaker or opposing battery will, 70 under this condition, be free to exert its influence in an opposite direction and throw a current in the course indicated by the spears across the track through the wheels and axle liable to be the most direct conductor in circuit, as indicated by the crossing spear at the rear of the dummy, the effect of the currents established being to reverse the polarity of the signal-magnets, and thus throw the signals to indicate "danger."

It will be perceived from the foregoing that I have produced an automatic system of signals, the movement of which to the respective positions of "danger" and "safety" is wholly due to electrical forces. The train or 85 other interposed obstruction affecting the current acts simply as a commutator or changer of the electric current from one direction to the other, and these intervening objects are the mediums which may be brought into operation in the entire circuit, through and by which the signals are actuated to assume or display the respective positions of "safety" and "danger."

As one of the elements of my system, I use 90 the gravity-weight, as shown in the drawings, for bringing the signals to display "danger" when the circuit is broken or diverted from the signal-magnets from any cause whatever. In this arrangement but one battery is absolutely essential to supply the current through the circuit, the battery, as E, the smaller, being used, if desired, merely as an adjunct or aid to the gravity attachment. In this arrangement, as in the arrangement of devices as heretofore described, the current holds the signals to "safety," that being the position of the signals when the batteries are on. As soon, therefore, as a train enters the block the battery will be cut out or short-circuited, and 100 the operation of the weight brought into play, resulting in bringing the signals to display "danger." The construction and arrangement of this appliance or gravity attachment has been described and stated hereinbefore; 105 but it may here bestate that if the circuit is broken from any cause whatever a danger-signal will be displayed. In other words, the electric current holding the signals to "safety" is a natural and not an artificial one. When 110 the battery is cut out or short-circuited, or if from any cause whatever the signal-magnets fail to be energized, a natural law of physics comes into operation and brings the signals to display "danger."

I make no specific claim in this application to the armature shown and described herein, as the same will be made the subject of another application for Letters Patent.

What I claim as my invention, and desire to 130 secure by Letters Patent, is—

1. In combination with an electrical railway-signal apparatus, an electro-magnet and a shaft arranged parallel to the cores of the

magnet, an armature having independent sectional wings of steel arranged with approaching ends and rigidly connected by a non-magnetic bar, and adjustably mounted on said

5 shaft to move on a plane parallel to the faces of the poles of the magnet, substantially as described.

2. In combination with an electro-magnet, a shaft mounted in bearings parallel to the cores of the magnet and provided with an angle-arm fixed thereto, an armature mounted on said shaft and consisting of two circular sections of steel rigidly connected together by a non-magnetic bar with their ends to approach, 15 and adapted to move toward and from the poles of the magnet on a plane parallel to the face of the poles of the magnet, a gravity-weight suspended from the angle-arm of the said shaft, and having its suspending cord carried in a 20 rotating pulley, substantially as described, and for the purpose stated.

3. In combination, a battery, a main conducting-wire having positive connection with the battery and extending along the line of road 25 and parallel thereto, an electro-magnet, an armature mounted thereon, a signal-disk adapted to be moved by said armature, a circuit-wire connected to said electro-magnet and extended parallel to the track, a signal-magnet 30 in connection with said wire and carrying an armature mounted thereon, a signal-disk adapted to be moved by the armature, a battery having negative connection with said last-named signal-magnet, and a circuit-wire con-

nected the free poles of both batteries, said 35 batteries being of relative different powers, substantially as described, and for the purpose stated.

4. In combination, a battery, a main conducting-wire having positive connection with the said battery and extending along the line of road and parallel thereto, an electro-magnet, 40 an armature mounted thereon, a signal-disk adapted to be moved by said armature, a circuit-wire connected to said electro-magnet and 45 extended parallel to the track, a signal-magnet in connection with said wire and carrying an armature adapted to move a signal-disk, a battery having negative connection with the last-named signal-magnet, and a gravity-weight 50 adapted to turn the signal-shaft, substantially as and for the purpose stated.

5. The combination of an electrical signaling apparatus with two opposing batteries in the same circuit, of different powers, 55 whereby the signals are held in position of "safety" by the stronger battery, and the signal is reversed by the lesser battery when its current is applied, and the signal is returned to "safety" when the stronger current is restored, substantially as described.

In testimony whereof I affix my signature in presence of two witnesses.

WILLIAM W. LE GRANDE.
